UNITED STATES PATENT OFFICE

JEAN H. KNOX, OF DALLAS, TEXAS, ASSIGNOR OF ONE-HALF TO ASSOCIATED FACTORIES CORPORATION, OF DALLAS, TEXAS, A CORPORATION OF DELAWARE

EXPANSION JOINT IN CONCRETE PAVEMENTS

Application filed February 18, 1929. Serial No. 340,827.

This invention relates to a means and method for increasing the effectiveness and endurance of pavement and more particularly to provide a dowel bar sleeve, whereby there is provided an expansion joint in the pavement.

As is well known to those familiar with the art of pavement construction it is necessary to provide a small space between adjacent portions of a concrete or other pavement to permit the pavement to expand or contract under weather conditions. This is usually done by leaving a small space in portions of the pavement and filling the space with some substance usually pitch or asphaltum. In this manner of construction, however, no means are provided for maintaining the pavement in true alinement, one portion with the other, when weather conditions expand or contract the parts.

The present invention provides a means and method for joining the parts, segments, portions or pieces of pavement in construction so that when expansion takes place the pavement will be permitted to move but remain in true alinement, one part with the other, the result being a perfectly smooth roadway.

While the means and method hereinafter disclosed are intended mainly for pavement it can be used wherever there is need for an expansion joint in concrete or other materials.

In the drawings forming a part of this specification:

Figure 1 illustrates a perspective and fragmentary view of a pavement, embodying the invention.

Figure 2 is a side elevational view of one of the dowel bars and coacting sleeve, whereby the expansion joint is formed.

Figure 3 is an enlarged side elevational view of a sleeve.

Figure 4 is a similar view of a bar, the bar and sleeve forming a unit.

Figure 5 is an end elevational view of the sleeve, showing its construction, and

Figure 6 is an end view of the bar.

Proceeding in accordance with the drawings, wherein specific parts are indicated by numerals, 1 denotes a cylindrical bar, prefer-

ably of steel or may be formed of any suitable material.

In connection with the bar 1 there is provided a tubular element or sleeve 2. The bar and sleeve form a unit, a number of which units, as depicted in Figure 1, are placed in the pavement parts or sections 3 and 4.

Attention is here directed to the construction of the sleeve or tubular element 2. This element is formed of a strip of resilient metal, of longitudinal shape, by bending the longitudinal sides of the strip over upon themselves as shown in Figure 5. The sides then are overlapped, the enclosed side or portion having a lip 5, bent at an angle to the cylindrical shape of the sleeve. This lip extends longitudinally of the sleeve and provides a means for engaging the bar 1, when the bar and sleeve are placed together in making up a joint in the pavement.

After the bar is inserted within the sleeve, this lip 5 is forced along its length against the inner wall of the sleeve. In this manner, the bar can be moved within the sleeve when movement takes place in the pavement, yet the sections of pavement 3 and 4 will remain firmly in alinement.

Of course, the bar and sleeve are not restricted to any particular length, but their relative proportions are such that, as shown in Figures 3 and 4, the sleeve is somewhat longer than the bar or rod 2.

In placing the sleeve and bar in the pavement, a sufficient number of sleeves and bars are connected together and, as illustrated in Figure 1, the assembled units are spaced across the divisional line or space 7 and embedded in the concrete or other substance forming the pavement.

The bars 1 and sleeves 2 are embedded in the pavement, but that portion of the bar inside the tube or sleeve will be free to move laterally.

The invention is not to be understood as being restricted to the particular form herein shown, but may be modified to come within the scope and meaning of the appended claims.

What is claimed as new is:

1. A device for preventing adjoining slabs

of concrete and cementitious material from moving out of horizontal alignment with each other during expansion and contraction which consists of a tubular member formed 5 by a sheet of metal rolled to form the member, the outer edge of the member overlapping the inner edge and the inner edge of the member being bent at an angle on itself and providing a longitudinal lip; and a rod 10 adapted to lie within the tubular member so that the rod will bear against said lip and the interior surface of the tubular member to hold the two parts in a tight embrace; the close contact of the rod and member fixing 15 the two together both before and during construction of the slabs in true relative positions and preventing pre-slipping of the rod and member but permitting the rod and member to move one within the other when the 20 slabs move apart from one another on expansion and draw together on contraction.

2. A device as claimed in claim 1 and for the purpose of forming a sliding joint for concrete slabs in pavement and roadways to 25 permit expansion and contraction of the slabs but preventing the slabs from moving out of vertical plane with each other; said device consisting of a hollow sleeve open at both ends, said sleeve formed by rolling a sheet of 30 metal to form the sleeve, the edges of the sleeve overlapping each other, the inner edge being bent inwardly at an angle and along the length of the sleeve; and a rod disposed within said sleeve; said rod being held tightly 35 within the sleeve and preventing slippage of the sleeve and rod from one another except at such time as the joint formed in the slabs expands or contracts during weather conditions, whereupon the rod will be permitted 40 to slide within the sleeve and the sleeve to slide over the rod.

3. A device as claimed in claim 1, said tubular member being formed by rolling so that 45 one edge overlaps the other thereby providing resiliency, the overlapping edges being movable upon each other to permit expansion as said rod is inserted into the member, said member having a smooth cylindrical surface on the outside from end to end.

4. A telescopic unit adapted to be embedded 50 within abutting ends of concrete slabs, comprising a dowel, a sleeve of substantially greater diameter than said dowel and spaced therefrom, and yielding frictional spacing 55 means for normally maintaining said sleeve and dowel in fixed longitudinal relation before the unit is embedded in the concrete, while permitting relative longitudinal movement of said sleeve and dowel to allow for 60 expansion and contraction of the concrete after the unit is embedded within the concrete.

5. A device for connecting abutting ends 65 of concrete slabs, comprising a plurality of telescopic units adapted to be embedded in

the concrete, each unit comprising a sleeve, and a dowel frictionally held within said sleeve and spaced from the sleeve throughout the principal portion of its perimeter.

6. A device of the character described comprising a sleeve having an inturned lip and 70 a dowel fitting within the sleeve of substantially less diameter than said sleeve, and frictionally engaged by said inturned lip, whereby slippage of said sleeve and dowel prior to use is prevented, while relative longitudinal 75 movement is permitted when the device is embedded in the abutting ends of concrete slabs to permit contraction and expansion of the slabs.

7. In a device for connecting abutting ends 80 of concrete slabs, a plurality of sleeves embedded in one of said ends and a plurality of rods embedded in the other end, said rod fitting within the sleeves, said sleeves being of substantially greater internal diameter than 85 said rods, and resilient spacing means interposed between the sleeves and rods for normally maintaining said sleeves and rods in fixed longitudinal relation, while permitting relative longitudinal movement on contraction 90 and expansion of the slabs in which the sleeves and rods are embedded.

In testimony whereof I affix my signature.
JEAN H. KNOX.
